Primary Examiner — Darlington Ly

(57) **CLAIM**

The ornamental design for a drone, as shown and described.

DESCRIPTION

1.-2. Drones

1.1 is a front elevation view of a drone, with wings extended, showing our new design;

1.2 is a rear elevation view thereof;

1.3 is a left side elevation view thereof;

1.4 is a right side elevation view thereof;

1.5 is a top plan view thereof; and

1.6 is a perspective view thereof.

2.1 is a front elevation view of a drone, with wings folded;

2.2 is a rear elevation view thereof;

2.3 is a left side elevation view thereof;

2.4 is a right-side elevation view thereof;

2.5 is a top plan view thereof; and

2.6 is a perspective view thereof.
